UNITED STATES PATENT OFFICE.

WILLIAM J. FLEMING, OF NEW YORK, N. Y.

DESIGN FOR A PUZZLE-BOARD.

SPECIFICATION forming part of Design No. 27,880, dated November 16, 1897.

Application filed October 7, 1897. Serial No. 654,464. Term of patent 3½ years.

To all whom it may concern:

Be it known that I, WILLIAM J. FLEMING, a citizen of the United States, residing in the city of New York, in the county and State of New York, have invented and produced a new and original Design for Puzzle-Boards, of which the following is a specification, reference being had to the accompanying drawing, forming a part thereof.

- 10 As shown in the drawing, which is a plan view of a puzzle-board showing my new design, the outline of the design is a circle A, within which and concentric therewith is a square B, the corners of which are upon radii 15 of the circle A. Within the square B is a picture representing an arctic scene, with mountains in the background and miners at work in the foreground, which may be printed, engraved, or embossed on the board.
- 20 The four corners of the square B may be

connected with the circle A by lines *a a a a*, forming parts of radii of the circle, which divide the space inclosed by the circle, outside of the square B, into four parts or panels, which surround the square B. Any suitable engraving or illustrations may be introduced in these panels.

Having described my invention, what I claim as new, and desire to secure by Letters Patent, is—

The design for a puzzle-board, as herein shown and described.

In testimony whereof I have hereunto subscribed my name this 5th day of October, A. D. 1897.

WM. J. FLEMING.
